Primary Examiner — Cynthia R Underwood(74) *Attorney, Agent, or Firm* — Jose Cherson Weissbrot(57) **CLAIM**

The ornamental design for a curtain rod bracket as shown and described.

DESCRIPTION

FIG. 1 is a front perspective view of a curtain rod bracket, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged view of section 9 in FIG. 3;

FIG. 10 is an enlarged view of section 10 in FIG. 5;

FIG. 11 is an enlarged view of section 11 in FIG. 5; and, FIG. 12 is a front perspective view of the curtain rod bracket in an environment of use.

The broken lines in FIG. 12 depict an environment of use which forms no part of the claimed design.

1 Claim, 11 Drawing Sheets(56)
